Application October 26, 1931, Serial No. 571,124

10 Claims. (Cl. 51—103)

This invention relates to improvements in machine tools and especially to improvements in grinding machines for grinding formed work pieces such as the conical valve seat on mushroom type valves.

An object of the invention is the provision of a grinding machine adapted for the accurate production of valve seats of the conical type such as mushroom valves.

Another object of the invention is the provision of improved means for supporting and rotating the valve about a predetermined axis.

A further object of the invention is the provision of improved means for backing up and steadyng the valve while being ground thereby insuring the grinding of one hundred percent valve seats.

Other objects and advantages of the present invention should be readily apparent by reference to the accompanying drawings illustrating the invention and described in the following specifications and it is to be understood that any modifications may be made in the structural details there shown and described within the scope of the appended claims without departing from or exceeding the spirit of the invention.

In the drawings:

Figure 1 is a plan view of a grinding machine embodying the principles of this invention.

Figure 2 is a sectional view taken on line 2—2 of Figure 1.

Figure 3 is a front elevation of a modified machine embodying the principles of this invention.

Figure 4 is a side elevational view of the machine shown in Figure 3.

Figure 5 is a sectional view taken on line 5—5 of Figure 4.

Figure 6 is a fragmentary sectional view taken substantially on line 6—6 of Figure 5.

Figure 7 is an elevational view partly in section as seen from line 7—7 of Figure 6 showing the drive of the work pieces and forming a detail of the invention.

Figure 8 is a front elevation of a centerless grinder embodying the principles of this invention.

Figure 9 is a top plan view of the machine shown in Figure 8.

Figure 10 is a sectional view taken substantially on line 10—10 of Figure 8.

Figure 11 is a fragmentary sectional view of a portion of the showing in Figure 10 illustrating the parts in a subsequent adjusted position.

Figure 12 is an end elevation of the machine

shown in Figure 8 and as seen particularly from line 12—12 of Figure 8.

Figure 13 is a sectional view taken on line 13—13 of Figure 10.

Throughout the several views of the drawings similar reference characters are employed to denote the same or similar parts.

The machine shown in Figures 1 and 2 comprises a bed 15 having formed on the upper surface thereof guideways 16 for guiding the grinding wheel carriage 17 in its movement relative to the bed. The carriage 17 has journaled there-in a spindle to which is secured a grinding wheel 18 suitably enclosed within a guard 19 carried by the carriage 17. The grinding wheel spindle is driven by any suitable or desirable means such as the motor 20 carried by the bed.

The carriage 17 is provided in its rear end with a nut 21 in threaded engagement with an adjusting screw 22 journaled at its outer end 20 in a housing 23 secured to the bed 15. Transmission means 24 is enclosed within the housing 23 and is connected at 25 with the screw 22. The other end 26 of the transmission means 24 is connected to the rear end of a shaft which extends through the bed from one end to the other. Secured to the outer end of the shaft 27 is a suitable feeding mechanism indicated generally by the hand wheel 28.

From the foregoing it will be noted that actuation of the feeding mechanism by the hand wheel 28 effects a relative feed of the carriage 17 and grinding wheel 18 relative to the bed.

Pivottally mounted at the forward end of the bed 15 and in line with the forward feed of the grinding wheel 18 are the work supporting and rotating mechanisms 29 and 30. These mechanisms are identical in construction being mounted on opposite sides of the grinding wheel 18 for simultaneous contact therewith at a point in the plane of the horizontal center of the grinding wheel and its spindle. It is deemed sufficient if but one of the work supporting and rotating mechanisms be described in detail. Accordingly, a housing 31 is provided which has a pivot bearing 32 encircling a vertical shaft 33 which acts as a pivot therefor. The housing is provided at opposite ends with bearing sleeves 34 and 35 in which is rotatably journaled a hollow shaft or spindle 36. A worm wheel 37 is secured to the shaft or spindle intermediate its ends and meshes with a worm 38 secured or integral with the vertical shaft 33. The housing 31 has on one end a cap plate 39 in which is threaded a limiting

abutment member 40 which extends part way through the hollow interior of the spindle 36.

Transversely mounted within the interior of the bed 15 is a driving shaft 41 having on one end 5 a pulley 42 for a transmission belt 43 which is in turn trained about a pulley 44 associated with the prime mover or motor 20. The driving shaft 41 has formed thereon a pair of worms 45 meshing with complementary worms or worm wheels 10 on the lower ends of the vertical shafts 33 whereby the said shafts are driven and consequently the hollow spindles 36.

As was noted above the hollow spindle 36 has extending partly therethrough an abutment or 15 limiting member 40 which terminates at a point spaced from the other end of the spindle and indicated by the numeral 46. Abutting the end 46 of the abutment 40 is the inner end of the work piece here illustrated as a mushroom valve 20 47. The conical valve seat 48 is adapted to engage the active face of the grinding wheel when the said valve is held in contact with the abutment 40.

The housing 31 is provided near the valve seat 25 end of the work piece with a stud 49 rotatably mounted therein but held against relative axial movement by a set screw or the like 50, see Figure 2. The stud 49 forms a bearing about which an arm 51 is adapted to oscillate. The arm 51 carries a spring pressed plunger 52 on the end 30 of an oscillating handle 53 which plunger enters suitable sockets formed in the stud 49 for holding said arm in operative and inoperative positions. The forward end of the arm 51 is offset as at 54 and carries the stud 55 of a thrust bearing 56. 35 A spring 57 surrounds the stud 55 and tends to axially shift thrust bearing from the arm toward the work piece. This movement under the influence of the spring 57 is resisted by the pin 58 passing through the outer end of the stud 55 and 40 lying on the exterior face of the offset portion 54. A head 59 having a semi-circular ball surface 60 abuts with the thrust bearing 56 on one end and with the valve head on the other whereby the valve is yieldingly held against the terminus 45 of the abutment pin 40 without offering frictional resistance to the rotation of the work as effected by the worm and worm wheel 37 and 38. The head 59 is held against inadvertent displacement with the thrust bearing 57 by means 50 of a pin 61 extending therefrom through the bearing and stud.

The work holding and rotating mechanisms 29 and 30 are adapted to lie in the positions indicated in Figure 1 during the actual grinding operation and are to be shifted through an angle of 45 degrees away from the grinding wheel to afford the replacement of the work piece within the spindle. This oscillation takes place as explained above about the axis of the vertical shafts 33. 55 The work mechanisms are locked in their innermost positions by means of a pin 62 having a nose 63 on one end thereof entering a socket 64 formed in the bed 15. The locking pin 62 is pivoted at its upper end 65 to an arm 66 which has intermediate its ends an enlarged opening 67 encircling the sleeve 68 which surrounds the stud 49. A pivot pin 69 passes through the arm 66, sleeve 68 and stud 49 for pivoting the arm of the stud whereby it may be oscillated in a vertical 60 plane for raising the locking pin 62. An operating handle 70 is secured to the arm 66 for actuating same and a spring 71 has one end 72 anchored to the housing 31 and the other end 73 secured to the arm at a point for tending 75 to actuate the locking pin to a locking position.

The operation of the mechanism is as follows: One of the work locating and rotating mechanisms 29 or 30 is oscillated outwardly through 45 degrees from the position shown in Figure 1. The handle 53 is then drawn to the left as seen in Figure 2 for disengaging the spring pressed plunger 52 from the stud 49 and then oscillated to remove the pressure head 59 from in front of the work. A new, unfinished work piece or mushroom valve is substituted for the finished one 10 now in the spindle 36. The handle 53 is then actuated in the opposite direction for causing engagement between the pressure head and the work whereupon the entire mechanism is oscillated about the axis of the shaft 33 to the position shown in Figure 1 for bringing about an operative engagement between the valve seat 48 of the work and the active face of the grinding wheel. The feeding mechanism 28 is now actuated to feed the grinding wheel into the work 20 and remove a definite amount of stock from the seat whereupon it is allowed to dwell for sparking out of the grinding wheel and work while the remaining work carrying and rotating mechanism is actuated to a position to have the work piece 25 therein replaced.

The modified structure illustrated in Figures 3 to 7 inclusive discloses a machine in which the work pieces contact the grinding wheel at points diametrically opposed to one another and in 30 which the work is fed relative to the bed toward the grinding wheel instead of feeding the grinding wheel toward the work as above described. This modification also includes a different type of work drive resembling more the principle of a 35 centerless grinder than the chuck type above described.

This modified machine comprises a base or bed 74 having rising therefrom a column 75. A bracket or arm 76 extends forwardly from the 40 column 75 and has journaled therein a grinding wheel spindle 77. The spindle 77 has secured to its upper end a grinding wheel 78 and at its lower end a reciprocating attachment 79 for imparting a relative axial movement to the grinding wheel and spindle. The spindle is further provided intermediate its ends with a sheave 80 for a multiple belt drive 81 which passes through an opening in the arm to the rear thereof. The multiple belts 81 are in turn trained about a 50 sheave 82 fast on the end of a motor shaft 83 rotatably guided by motor 84. The motor 84 is bolted or otherwise secured to the rear of the column 75 and may preferably be placed within a cored opening formed in the rear face of the 55 column.

The upper end of the column 75 is formed into a rail 85 on the outer face of which is provided a dove-tailed guide 86. Mounted on the dove-tailed guide 86 for movement relative thereto are a pair of work supporting and rotating mechanisms 87 and 88. These mechanisms are identical in construction and it is deemed sufficient if but one of them be described in detail. It might be noted that the said mechanisms are 60 independently actuated toward and from one another respectively by cross feed screws 89 and 90 carrying on their outer ends hand wheels 91 and 92.

Each of the mechanisms consists of a housing 70 93 having a bearing for oscillatory movement about a worm shaft 94 that is carried by a slide 95 on the dove-tailed guideway 86. Mounted in bearings provided by the housing 93 is a drive shaft 96 having secured thereto a worm wheel 75

97 meshing with a worm 98 on the shaft 94. The drive shaft 96 is provided with an enlarged counter-bore 99 in which is positioned for axial movement relative thereto a driving member 100. The member 100 has projecting from it a pin 101 received in a reduced bearing 102 of the shaft 96. The shaft 96 and pin 101 are keyed together for unitary rotation, but permitting axial sliding one with respect to the other. Surrounding the pin 101 and enclosed within the counter-bore 99 is a coiled spring 103 abutting on opposite ends with the base of the bore 99 and the driving member 100 for actuating said driving member 100 outwardly from the bore 99. The driving member 100 has integral therewith a driving head 104 in the outer end of which is formed a conical socket 105 into which the inner end of the valve stem 106 is inserted. The valve driving head 104 is journaled in a bushing 107 held in the housing 93 by any suitable or desirable means. Spaced from the bushing 107 and enclosed within the housing 93 is a member 108 which has a seat 109 formed at the outer end thereof for engagement with the seat 110 of the valve being ground. The member 108 is slidably mounted in the housing 93 for sliding movement relative thereto but pinned against rotational movement. A spring 111 is interposed between the pinned bushing 107 and the member 108 tending to force the member 108 outwardly and maintain contact between the work seat and itself. It will be noted from the drawings that the seat 109 of the member 108 contacts with the work seat for only a portion of its extent being cut away at the point adjacent the grinding wheel to permit the grinding wheel to have access to the work.

Secured to the housing 93 by bolts 112 is a bracket 113 having at the end thereof a lug 114 contacting with a lug 115 of arm 116. A pivot pin 117 extends through the lugs 114 and 115 for pivotally securing the arm to the bracket. At its outer end the arm 116 carries a thrust bearing 118 similar to the bearing above described to which reference may be had for further details. The said bearing and parts associated therewith support the pressure head 119 for contact with the outer end of the valve tending to urge the valve into contact with the driving head 104 and resiliently maintaining contact between the valve seat 110 and the seat 109 of the steady-rest member 108.

The worm shaft 94 is provided on its inner end with a worm wheel 124 which meshes with a worm 125 splined on transverse shaft 126. Shaft 94 is journaled in a bearing 123 integral with the slide 95 and extending rearwardly therefrom through the rail 86 to the interior of the upper end of the column 75. Also carried by the shaft 94 at its extreme inner end is a bracket 127 which has arms 128 and 129 through which suitable apertures are formed for receiving the end journals of the worm 125.

The splined drive shaft 126 is driven through a pair of bevel gears 130, see Figure 4, one of which gears is secured to the end of the shaft 126 and the other being secured to a driving shaft 131 journaled in bearings 132 carried by the column 75. The shaft 131 at its other end carries a second bevel gear 133 meshing with a complementary bevel gear 134 on the upper end of a vertical drive shaft 135. This shaft 135 is journaled at one end in the bearing 132 and at the other end in a bearing 136. Below the bearing 136 the shaft 135 has keyed or otherwise secured

to it a spur gear 137 meshing with driving gear 138 on the end of motor shaft 83.

The operation of the mechanism disclosed in Figures 3 to 6 inclusive is as follows: The arm 116 of one of the mechanisms 87 and 88 is actuated outwardly to release and permit the replacement of the work piece carried thereby whereupon it is swung in a direction to effect engagement between the active face of the grinding wheel and the seat of the valve to be ground. The proper hand wheel 91 or 92 is then actuated to feed the work into the wheel the desired amount. The grinding continues on this work piece until the work has been reduced to the desired size. It should be noted that the work is rotated merely through the frictional engagement between the driving seat 105 of the head 104 and the stem of the work. The work is guided and maintained by the steadyrest seat 109 formed on the member 108. This seat 109 prevents any vibration or shifting of the axis of the valve insuring the grinding of the seat absolutely concentric with the axis of rotation determined by the forcing of the work into the conical seat 105. It should further be noted that the grinding wheel tends to rotate the work at its own peripheral speed which speed is controlled, modified and regulated by means of the drive between the worm and worm wheel 97 and 98.

During the grinding of the work piece carried by one or the other of the work supporting mechanisms 87 and 88 the other mechanism is being loaded so that as soon as the grinding operation on one mechanism ceases it immediately commences on the other, thereby insuring continual production from the machine.

The modification shown in Figures 8 to 13 inclusive illustrates a centerless grinder for producing a hundred percent seat on the mushroom type valve. This machine is capable of wide adjustments for operating on work pieces of different sizes and forms. It operates on a single work piece instead of a plurality of work pieces and can be very readily loaded and automatically ejected.

This machine comprises a bed 139 having rising therefrom a pedestal bearing 140 enclosing a spindle to which is secured a grinding wheel 141. The bed 139 is further formed on its upper surface with a bearing 142 forming a guide for a slide 143 mounted thereon. Superimposed on the slide 143 is a second slide 144 carrying the head 145 in which is journaled a spindle 146 for regulating wheel 147. The grinding wheel and regulating wheel have their active surfaces spaced from one another a distance to form a grinding throat in which is mounted the work supporting mechanism. This work supporting mechanism comprises a block 148 bolted or otherwise secured to the inner end 149 of the slide 143. The slides 143 and 144, work rest 148 and work 150 supported thereby, are adapted to be actuated as a unit toward the grinding wheel. For this purpose the slide 144 has swiveled therein a nut 151 threadedly engaged with an adjusting screw 152 rotatably carried by a bracket 153 secured to an extending portion of the bed. Beyond the bearing 153 a pilot or hand wheel 154 is secured to the screw whereby it may be rotated. For normally feeding the work toward the grinding wheel and retracting same therefrom to permit the replacement thereof, the nut 151 is provided with a handle 155 adapted for oscillation about the axis of the screw 152 and carrying with it the nut 151.

The work piece is held on the work rest blade and ejected therefrom by hydraulic or pneumatic pressure which is controlled by a suitable valve for connecting the pressure line with various ports. Accordingly, the bracket or housing member 148 has bolted thereto a valve 156 including a pivotally mounted handle 157 to be operated by the double cam shaped finger 158 carried by arm 159 by means to be described later. Hydraulic pressure, preferably air, is introduced to the valve 156 from a suitable source through the conduit 160 and port 161 passing from the valve 156 through suitable ports 162 and 163 to opposite ends of a cylinder 164 formed in the block or housing 148. The cylinder 164 contains double ended piston 165 which has extending from it a rod 166 terminating in a tapered nose 167. The tapered end 167 engages a roller 168 rotatably mounted on pin 169 joining the fingers of fork 170 secured to for movement with shaft 171. A pin 172 having a clevis 173 at its one end is pivotally mounted by means of the clevis to the pin 169 and the other end of the pin 172 extends through a guide 174. A spring 175 surrounds the pin 172 and abuts on opposite ends with the guide 174 and clevis 173. Externally of the housing 148 the shaft 171 has secured to it for movement therewith an arm 176 having pivotally secured to its upper end a second arm 177 which rotatably supports end pressure roller 178. A spring 179 has one end secured to pin 180 carried by the arm 177 and its other end secured to the housing 148. The shaft of end pressure roller 178 has journaled on it a cam roller 181 for engaging the cam face 182 of cam 183 secured to the housing 148 by any suitable or desirable means. The cam 183 determines the contact of the end pressure roller 178 with the end of the work piece and causes the said roller to approach and engage the said end work.

45 The automatic work ejecting mechanism comprises an adjusting screw 184 having a knurled operating head 185 threadedly received in a bracket 186 in which the end of a tubular housing 187 is secured. The ejector plunger 188 is spaced from the end of the work and terminates in a piston 189 and has a spring 190 surrounding it. A bracket 191 which secures the housing 187 to the bracket or block 148 is provided with a threaded perforation 192 receiving the threaded end 193 of an adjusting screw 194 journaled in a depending portion of the bracket 186. A knurled knob 195 is secured to the end of the adjusting screw 194. A conduit 196 connects the end of the cylinder containing the piston 189 with the right hand end of the cylinder 164 so that as soon as pressure is introduced to the end of the cylinder 164 it is simultaneously introduced in the cylinder of piston 189. However, the piston 189 is not actuated until after the piston rod 166 has been shifted because the side pressure rollers 196', to be described in detail later, hold the work against movement until they are released from the work by the said piston rod 166.

70 In order to hold the work on the work rest blade and in contact with the regulating wheel there is provided side pressure rolls 196' mounted on a shaft 197 carried in the end of an arm 198. This arm 198 is secured to the upper end of a vertically mounted shaft 199 carried by the block or housing 148. Secured to the shaft 199 at its lower end is a second arm 200 carrying at its free end a roller 201. The arm 200 is enclosed within a cover 202 secured to block or housing 148. The arm 200 has formed therein, intermediate its ends, a socket 203 in which is mounted a spring 204 abutting on its outer end with the cover 202 and exerting a yielding pressure on the arm 200 in a clockwise direction which through the vertical shaft maintains contact between the side rollers and the work. The roller 201 is held in engagement with the adjacent side of the piston rod 166 which is provided with a relieved portion 205 and a cam face 206.

The piston 165 is actuated to the left as seen in Figure 10 which causes the cam face 206 to engage the roller 201 and actuate the arm 200 which removes the side pressure rollers from the work so that it can be ejected from the machine.

The arm 159 for actuating the valve 156 is secured to a short shaft 207 connected by a universal joint to one end of a rod 208. The rod 208 extends from the grinding throat along the rear wall of the machine to the end thereof at the right, as seen in Figures 8 and 9, where it is connected by a second universal joint to a splined shaft 209, see Figure 12. The splined shaft 209 is mounted in a sleeve member 210 for rotative movement with the sleeve member but the said sleeve member has axial movement relative to the splined shaft 209. The sleeve member 210 has secured to it or formed integral therewith a segmental gear 211 and is journaled in a bracket 212 secured to the upper slide 144. Bearing bosses 213 are carried by the bracket 212 through which is axially slidably a rack shaft 214 having rack teeth 215 thereon for engagement with the segmental gear 211, as well as rack teeth 216 for engagement with the teeth of a segmental gear 217 associated with the operating handle 155.

With the parts as shown in Figure 10 the handle 155 of Figure 12 is in a horizontal position with the arm 159 in a position to dispose the cam plate 159 below the valve handle 157 so that at the completion of the grinding operation the handle 155 is raised upwardly for raising the arm 157 from the position shown in Figure 10. This movement of the arm 157 in a counter clockwise direction causes cam face 218 to engage the roller 219 on the arm 157 for connecting the hydraulic pressure of line 160 through the valve 156 with the right hand ends of cylinders containing the pistons 165 and 189. The piston 165 immediately moves toward the left, as seen in Figure 10, but the piston 189 remains stationary. The piston 165 carries with it the rod 166 and continues to move until the nose 167 has, through the roller 168, actuated the parts 170, 172, 176, 177 and 178 to the position shown in Figure 11. At this time the end pressure roll 178 is out of the path of movement of the work 150. Continued movement of the rod 166 then moves the side or lateral pressure rolls 196' from the work whereupon the pressure behind the piston 189 actuates same to the left and ejects a work piece from the grinding throat. At this time the cam face 221 has passed from the roller 219 whereupon the pressure is cut-off from the left hand ends of the cylinders so that the spring 190, surrounding the piston rod and compressed on the ejecting stroke, may expand and return piston 189 to the normal end of its stroke against the adjustable abutment 184. The grinding throat is now enlarged to the limit of its movement with the handle 155 in the position shown

in Figure 12 and a new unfinished work piece is mounted in the grinding throat.

The handle 155 is now actuated in a counter clockwise direction to feed the new unfinished work relative to the grinding wheel whereupon the cam face 221 on the cam plate 158 engages the roller 219 of the arm 157 for oscillating said arm in the opposite direction and connecting the pressure in conduit 160 with the forward face 10 of piston 165 to retract the rod 161 and permit the expansion of spring 175 whereupon the roller is yieldably shifted up the cam face 182 into engagement with the end of the work.

What is claimed is:

1. In a grinding machine for grinding the tapered face on angularly related surfaces, the combination of a bed, a grinding wheel rotatably journaled thereon, a work supporting mechanism, means for disposing the axis of the work and grinding wheel at an angle to one another corresponding to the angle of the surface being ground, means frictionally rotating the work, a steady rest member engaging the tapered surface for steadyng same while it is being ground, means yieldably urging the work and wheel relative to one another to maintain contact between the grinding wheel and work, means rendering the yielding means inoperative, and means for automatically ejecting the work from the work supporting mechanism when the yielding means have been rendered inoperative.

2. In a grinding machine for grinding the tapered valve seat on mushroom type valves, the combination of a bed, a grinding wheel rotatably mounted thereon, means supporting a work piece for rotation about an axis angularly related to the axis of a grinding wheel so as to dispose the active face of the grinding wheel parallel with the valve seat being ground, means engaging the valve seat as it is being ground to steady same during the grinding operation, said means engaging substantially the entire valve seat being cut away at the point proximate the grinding wheel.

3. In a grinding machine for grinding the tapered valve seat on mushroom type valves, the combination of a bed, a grinding wheel rotatably mounted thereon, means supporting a work piece for rotation about an axis angularly related to the axis of a grinding wheel so as to dispose the active face of the grinding wheel parallel with the valve seat being ground, means engaging the valve seat as it is being ground to steady same during the grinding operation, said means engaging substantially the entire valve seat being cut away at the point proximate the grinding wheel, means yieldably engaging one terminus of the work for urging it toward the grinding wheel, and means frictionally engaging the other terminus of the work for effecting its rotation.

4. In a grinding machine of the class described, the combination of a bed, a grinding wheel rotatably mounted thereon, a plurality of work supporting and rotating mechanisms carried by the bed for supporting work pieces for contact with the grinding wheel at a plurality of points on the grinding wheel, said work supporting and rotating mechanism comprising a pivotally mounted housing, a spindle journaled in the housing, means associated with the spindles for frictionally engaging the work to rotate it, means yieldably urging the work relative to the supporting and driving means into engagement with the grinding wheel, and means for rendering said yieldably urging means inoperative.

5. In a grinding machine of the class described, the combination of a bed, a grinding wheel rotatably mounted thereon, a plurality of work supporting and rotating mechanisms carried by the bed for supporting work pieces for contact with the grinding wheel at a plurality of points on the grinding wheel, said work supporting and rotating mechanism comprising a pivotally mounted housing, a spindle journaled in the housing, means associated with the spindles for frictionally engaging the work to rotate it, means yieldably urging the work relative to the supporting and driving means into engagement with the grinding wheel, means for rendering said yieldably urging means inoperative, and means for effecting a relative feed between the work supporting mechanisms and the grinding wheel.

6. In a grinding machine of the class described, the combination of a bed, a work rest blade mounted on the bed for peripherally supporting the work piece to be operated upon, a grinding wheel rotatably mounted on the bed on one side of the work rest blade having its axis disposed at an angle to the axis of the work rest blade so that an angular face is formed on the work on the blade, a regulating wheel rotatably mounted on the bed on the other side of the blade for engagement with the work piece for effecting and controlling its rotation, a work rest member on the blade adapted to contact with the angular surface being formed on the work during the grinding operation, said work rest member having an opening therein whereby the grinding wheel has access to the work, and lateral pressure means for holding the work on the blade in contact with the regulating wheel.

7. In a grinding machine of the class described, the combination of a bed, a work rest blade mounted on the bed for peripherally supporting the work piece to be operated upon, a grinding wheel rotatably mounted on the bed on one side of the work rest blade having its axis disposed at an angle to the axis of the work rest blade so that an angular face is formed on the work on the blade, a regulating wheel rotatably mounted on the bed on the other side of the blade for engagement with the work piece for effecting and controlling its rotation, a work rest member on the blade adapted to contact with the angular surface being formed on the work during the grinding operation, said work rest member having an opening therein whereby the grinding wheel has access to the work, lateral pressure means for holding the work on the blade in contact with the regulating wheel, and yielding terminal means for terminal engagement with the work to axially shift same relative to the blade into contact with the grinding wheel.

8. In a grinding machine of the class described, the combination of a bed, a work rest blade mounted on the bed for peripherally supporting the work piece to be operated upon, a grinding wheel rotatably mounted on the bed on one side of the work rest blade having its axis disposed at an angle to the axis of the work rest blade so that an angular face is formed on the work on the blade, a regulating wheel rotatably mounted on the bed on the other side of the blade for engagement with the work piece for effecting and controlling its rotation, a work rest member on the blade adapted to contact with the angular surface being formed on the work during the grinding operation, said work rest member having an opening therein whereby the grinding wheel has access to the work, lateral pressure means

for holding the work on the blade in contact with the regulating wheel, yielding terminal means for terminal engagement with the work to axially shift same relative to the blade into contact with the grinding wheel, and means for rendering the lateral and terminal work engaging means inoperative and for automatically ejecting the work from the work rest blade.

9. In a grinding machine of the class described 10 for grinding a surface of revolution angularly related to the axis of rotation comprising a work support for the work, means frictionally engaging and rotating the work while supported, a grinding wheel having an operative face rotatable in a plane parallel with the surface of revolution to be ground, a steady rest member having a seat thereon contrageneric to the surface of revolution being ground for engagement therewith during the grinding operation, said steady rest member engaging substantially the entire surface

being ground, but having a cut-away portion whereby access is had thereto by the grinding wheel, and yielding means for axially urging the work piece toward the grinding wheel and steady rest member.

10. In a grinding machine of the class described for grinding a surface of revolution angularly related to the axis of rotation comprising a work support for the work, means frictionally engaging and rotating the work while supported, a grinding wheel having an operative face rotatable in a plane parallel with the surface of revolution to be ground, and a steady rest member having a seat thereon contrageneric to the surface of revolution being ground for engagement therewith substantially throughout its length and breadth during the grinding operation.
